Gagenein & Hayes LLP

(57) **CLAIM**

The ornamental design for an inserting aid for optical discs
having a special shape, as shown and described.

DESCRIPTION

FIG. 1 is a perspective view of this invention;
FIG. 2 is a top or bottom view of FIG. 1;
FIG. 3 is a back elevation view of FIG. 1;
FIG. 4 is a front elevation view of FIG. 1;
FIG. 5 is a right side elevation view of FIG. 1; and,
FIG. 6 is a left side elevation view of FIG. 1.
